(57) **CLAIM**

The ornamental design for a sunscreen sleeve, as shown and described.

DESCRIPTION

FIG. 1 is a front, left perspective view of a sunscreen sleeve, showing my new design;

FIG. 2 is a rear, right perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 1;

FIG. 14 is an enlarged view of detail 14 in FIG. 1;

FIG. 15 is an enlarged view of detail 15 in FIG. 1; and,

FIG. 16 is an enlarged view of detail 16 in FIG. 1.

The dashed broken lines illustrate portions of the sunscreen sleeve which form no part of the claimed design.

The short-short-long dashed broken lines immediately adjacent to the claim area are for the purposes of illustrating the boundaries of the sunscreen sleeve, and form no part of the claimed design.

The dash-dot-dash broken lines are for notating enlarged views and form no part of the claimed design.

1 Claim, 16 Drawing Sheets
